UNITED STATES PATENT OFFICE.

JUBERT G. MALOUF, OF LA SALLE, NEW YORK.

LOCK.

Application filed July 18, 1925. Serial No. 44,620.

My invention relates in general to locks, and in particular to a permutation or combination lock.

Some of the objects of my invention have been to provide a lock of this nature which shall be durable in construction, and inexpensive to manufacture.

Another object has been to provide a lock which may have its combination easily changed without disassembling.

Moreover, my device is provided with means whereby it shall be impossible for an unauthorized person to detect the combination by feeling.

Furthermore, my device is of such a nature that it is susceptible of a number of various uses.

The above objects and advantages have been accomplished by the device shown in the accompanying drawings, of which:

Fig. 1 is an enlarged, longitudinal, sectional elevation of my complete device.

Fig. 2 is a transverse, sectional elevation thereof taken on line 2—2 of Fig. 1 and looking in the direction indicated by the arrows.

Fig. 3 is a similar sectional view taken on line 2—2 of Fig. 1, but looking in a direction opposite to that indicated by the arrows.

Fig. 4 is a transverse, sectional elevation taken on line 4—4 of Fig. 1.

Fig. 5 is an enlarged sectional view of one of the lock discs.

Fig. 6 is a similar view of one of the tumblers.

Fig. 7 is a rear face elevation of the device showing it adapted for use as a keyhole lock or guard.

Fig. 8 is a side elevation of the device showing it adapted for use as a padlock.

Referring to the drawings, 10 represents the casing of my device which is cup-shaped. Mounted within the interior of the casing 10 is a plurality of tumblers, each comprising a lock disc 11 and a tumbler disc 12, corresponding in number to the number of combinations desired. In the drawings, but three of such lock discs are shown, it being obvious that a greater or lesser number may be provided if desired.

The tumbler disc 12 which is provided for each of the lock discs 11 is mounted within a recess 13 provided in each of the lock discs. Each of the tumbler discs is carried by the flanges 14 and 15 provided

on a tumbler hub 16. The pressure of the flanges 14 and 15 against the tumbler disc 12 is such that it will firmly hold the disc in position, but when considerable force is applied, the disc may be made to move and rotate about the hub, whereby the combination may be easily and quickly changed. The hub 16 is provided with annular extensions 17 and 18, which engage with bearing apertures 19 formed in the lock discs. By reference to Figures 1 and 6, it will be seen that the annular extension 17 of one hub 16 and the annular extension 18 of the adjacent hub are in contact with each other and that the aperture 19 of the lock disc 11 forms a bearing for the two annular extensions of adjacent hubs. Each hub 16 is provided with a central bore 21 and with an annular recess or counterbore 22. A longitudinal groove or keyway 23 is provided in the portion of the hub which is provided with the bore 21 for purposes to be hereinafter described. The flange 15 of the hub is provided on its periphery with a number of indentations 20. These indentations are engageable with a spring 24 which is preferably held by the lock disc 11. The spring is so designed that it will engage with the notches of the flange and serve to temporarily hold it in any set position. Each of the tumbler discs 12 is provided with a notch 35 in its periphery for purposes to be hereinafter described.

A cover 25 is provided for the body 10 and is preferably set into a recess 26 and against a shoulder 27 formed therein. The cover may be secured in position by any suitable means, but since the lock discs 11 must be prevented from rotation, it is convenient to secure the cover in position by means of a number of rivets 28 which are passed through the cover, the lock discs and the bottom of the casing 10. The cover is provided with a hub 29 having a bearing for the operating stud 30, which is slidable and rotatable within the hub. The stud is provided with an operating knob 31 having an index finger 32. The hub is provided with a number of longitudinal scores or marks 33, corresponding in number to and registering with the number of notches 20 provided in the flange 15 of the hub 16. Numerals 34 are preferably provided for the scores 33 and these are stamped upon the face of the cover 25. The inner end of the operating stud 30 is engageable with the bore 21 of each tumbler hub 16, and a pin

36 is carried by the end of the operating stud and radially arranged so as to engage the grooves 23 formed in the tumbler hubs. Since the recess 22 in each of the tumbler hubs is larger than the diameter described by the pin 36, the pin will be free to move around in the recess without causing the rotation of the tumbler hub. When, however, the pin is moved in the groove 23, the tumbler hub 16 may then be rotated by the rotation of the operating stud 30. The operating stud 30 is provided with a number of annular semi-circular grooves 37, equal in number to the number of tumbler discs. A spring 38 is carried by the hub 29 of the cover, and its end 39 passes through a slot 40 formed in the hub, whereby it is engageable with any one of the grooves 37 when such groove is moved into registerable position therewith. The grooves are so arranged that the spring 38 will engage with one of them when the pin 36 is in engagement with the groove 23 of either of the hubs. This forms a flexible stop for the longitudinal movement of the operating stud 30 when the lock is being manipulated.

A lock bar 41, preferably of rectangular cross-section, is passed through suitable slots formed in the cover 25, the edges of the lock discs 11, and through the bottom of the casing 10. This lock bar is provided with a number of notches 42 in its edge which is adjacent the tumbler discs, and with which the tumbler discs are engageable. As shown in Fig. 1, the tumbler discs lie in these slots and thus lock the device. When, however, the notches 35 of each of the discs are brought in registering position with the lock bar, the bar may be freely slid out of the lock.

Arranged in a recess 45 of the cover 25 is a floating disc 46. This disc is mounted upon the operating stud 30 and is provided with a key 47 extending inwardly from its central aperture and engaging a keyway 48, provided in the operating stud, whereby this disc will be rotated when the stud is rotated. A notch 35 is provided in the periphery of this disc like the notches 35 of the other discs.

When my device is locked and it is desired to unlock the same, the combination being known, the operating stud 30 is moved axially so as to preferably engage the hubs in succession. The first position will be that shown in Fig. 1 where the pin 36 of the operating stud is in engagement with the groove 23 of the first tumbler hub. This hub is then rotated until the index finger is brought opposite the numeral of the combination corresponding with the first tumbler, after which the operating stud is pushed inwardly until the pin 36 is out of engagement with the groove 23 of the first hub. The stud, while being rotated, is now urged in-

wardly against the next succeeding tumbler hub, whereupon the pin 36 will be brought into engagement with the groove 23 of the next succeeding tumbler hub. The axial movement of the stud is then continued until the end 39 of the spring 38 engages with the middle groove 37 on the stud, which will act as a temporary stop. When the operating stud is in this position, it is connected with the second tumbler hub 16 and the same may now be rotated until the index pin is opposite the number corresponding to this tumbler. The operating stud is then moved axially, as just above described, until the pin 36 engages with the groove 23 of the last tumbler hub and until the spring 38 engages with the last groove 37 on the stud, whereupon the last tumbler may be rotated to a predetermined number. The operating stud is now moved axially to a position where the pin 36 will lie in the recess 22 of either of the tumbler hubs, and the floating disc 46 is then rotated to bring its slot 35 into registering position with the lock bar 41, whereupon the same will be released and may be withdrawn. The slot 49, formed in the lock bar for the floating disc 46, is narrower than the slots 42 for the tumbler discs, and the reason for providing the floating disc is that the notches 35 of the tumbler discs 12 may not be felt by an unauthorized person as they are being moved past the lock bar.

My device is of such a nature that it is applicable to various uses. In Fig. 1, I have shown it equipped for use as a keyhole guard or lock. When so used, a lock pin 51 is carried near the top of the casing, and this lock pin is provided with a detent pin 52 extending at right angles with the axis of the lock pin and arranged at an angle with the diametrical center line of the device. This lock pin is arranged immediately above the lock bar 41, and when the device is used as a keyhole guard, the lock pin is first inserted in the round part of the key hole, whereupon the entire device is slightly rotated so as to bring the lock bar in registering position with the slotted part of the key hole. The lock bar is then inserted in the slotted part of the keyhole and the device locked by rotating the tumbler discs 12 to various positions. By reference to Fig. 7, where the keyhole is shown in dotted lines, it will be seen that the detent pin 51 will prevent the device from being withdrawn from the keyhole.

Another use of my device is that of a padlock, as shown in Fig. 8. When so used, a hasp 53 is provided, which is formed with a flattened end 54, which takes the place of the lock bar 41, and with an end 55 which passes through an opening 56 formed in the body 10 and arranged preferably at a point diametrically opposite the lock bar.

It is obvious that when the lock bar 41 or the hasp 53 is inserted in the device, the tumblers are set by being rotated, as hereinbefore described, to various positions.

5 Obviously, some modifications of the details herein shown and described may be made without departing from the spirit of my invention or the scope of the appended claims, and I do not, therefore, wish to be limited to the exact embodiment of the form 10 herein shown and described, the form herein shown being merely a preferred form.

Having thus described my invention, what I claim is:

15 1. A lock comprising a body, a plurality of lock discs non-rotatably mounted within the body, each lock disc having a central bore and a concentric recess, a lock bar passing through the body and the lock discs and formed with a plurality of notches, a tumbler hub mounted in the recess of each lock disc, each of the discs being rotatable through a complete circle without rotating any of the other discs, each tumbler hub 20 having an annular extension at each side for engagement with the bores of adjacent lock discs, a tumbler disc carried by each tumbler hub, and an operating stud engageable with the tumbler hubs for rotating the 25 same independently and one at a time.

20 2. A lock comprising a lock bar, a plurality of circular-shaped tumbler members in co-operative relation with the lock bar, each tumbler member comprising a tumbler hub, 35 formed with a central bore and recess, the bore having a groove extending therefrom, and a tumbler disc adjustably carried by the hub and formed with a notch for engagement with the lock bar, a floating disc engageable with the lock bar, and an operating 40 stud having a pin engageable with the recesses and grooves of the hubs.

3. A lock comprising a body, a plurality of lock discs non-rotatably mounted within 45 the body, a lock bar carried by the body and passing through the lock discs, the lock bar having a plurality of notches, a tumbler hub rotatably carried by each lock disc, each tumbler hub having a notched flange, a 50 spring carried by each lock disc and engageable with the notches of the hub flange, a tumbler disc carried by each tumbler hub and in co-operative relation with the lock bar, and an operating stud for rotating the 55 tumbler hubs independently and one at a time.

4. A lock comprising a lock bar formed with a plurality of notches, a plurality of circular tumblers engageable with the notches 60 of the lock bar, each of the tumblers being

rotatable through a complete circle without rotating any of the other tumblers, and an operating stud for individually operating either of the tumblers independently of the others, the lock bar being operated independently of the operating stud. 65

5. A lock comprising a detachably mounted lock bar, a plurality of circular tumblers in co-operative relation with the lock bar, each of the tumblers being rotatable through a complete circle without rotating any of the other tumblers, and an operating stud for rotating the tumblers one at a time. 70

6. A lock comprising a lock bar, a plurality of circular tumblers in co-operative 75 relation with the lock bar, each of the tumblers being rotatable through a complete circle without rotating any of the other tumblers, and an operating stud for rotating the tumblers one at a time, the stud being operable in a plane parallel with the path of movement of the lock bar. 80

7. A lock comprising a lock bar, a plurality of circular tumblers in co-operative 85 relation with the lock bar, each of the tumblers being rotatable through a complete circle without rotating any of the other tumblers, and an operating stud for rotating the tumblers one at a time. 85

8. A lock comprising a lock bar, a plurality of independently operating circular tumblers in co-operative relation with the lock bar, an operating stud for rotating the tumblers one at a time, and a floating disc engageable with the lock bar. 90

9. A lock comprising a lock bar formed with a plurality of notches, a plurality of circular tumblers engageable with the notches of the lock bar, each of the tumblers being rotatable through a complete circle without rotating any of the other tumblers, a floating disc engageable with the lock bar, and an operating stud for individually operating either of the tumblers independently of the others. 100

10. A lock comprising a lock bar, a plurality of circular tumblers in co-operative 105 relation with the lock bar, each of the tumblers being rotatable through a complete circle without rotating any of the other tumblers, each tumbler comprising a tumbler hub and a tumbler disc adjustably carried by the tumbler hub, the lock bar being formed with a plurality of notches for engagement with the tumblers, and an operating stud for operating the tumbler hubs independently 110 of each other and one at a time. 115

In testimony whereof, I have hereunto signed my name.

JUBERT G. MALOUF
